(57) CLAIM

The ornamental design for a mechanical pickleball scorekeeper as shown and described.

DESCRIPTION

FIG. 1 is a perspective view of a mechanical pickleball scorekeeper, showing the new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The broken line showing of numbers is for the purpose of illustrating portions of the invention that form no part of the claimed design.

All surfaces not shown form no part of the claimed design.

1 Claim, 3 Drawing Sheets
